SURGICAL BONE CLAMP

George S. Hackett, Canton, Ohio, assignor to
Harry Herschel Leiter, Warsaw, Ind.

Application September 27, 1941, Serial No. 412,593

3 Claims. (Cl. 128—346)

This invention relates to improvements in a surgical bone clamp for use in reduction of a bone fracture and during application of a cincture by which to maintain fixation of bone fragments for a more or less protracted period of time.

An object of the invention is to afford an adjustable instrument for temporarily holding in place, after reduction thereof, the fragments of a fractured bone, having means to facilitate encirclement of the bone with a cincture at the point of the reduced fracture.

Another object of the invention is to provide in a clamp for reduced bone fractures, opposing jaws between which is secured the bone fragments during application of a cincture thereto, one of which jaws is adjustably movable toward and from the other jaw, and which also is supported so that it automatically drops out of the way to permit unobstructed removal of the instrument from engagement with the bone out through the incision in the surrounding flesh after the cincture has been applied.

And a further object of the invention is to provide a cincture for use in conjunction with a bone clamp so formed that, while the clamp is in operative position and the cincture is being applied, encirclement of the bone by the cincture wire is readily accomplished without departure of the wire from the intended course.

Other objects and advantages of the invention appear in the following description.

An illustrative embodiment of the invention is shown in the accompanying drawing, in which:

Fig. 1 is a side elevational view of an instrument in which the invention is incorporated, parts thereof being broken away;

Fig. 2 is a top plan view of the instrument projected from Fig. 1;

Fig. 3 is a cross-sectional view showing a front end portion of the instrument, the section being on the line 3—3 of Fig. 2;

Fig. 4 is another cross-sectional view of the instrument showing the movable jaw, the section being on the line 4—4 of Fig. 2;

Fig. 5 is a side elevational view of a cincture used with the instrument, shown in its initial form with a portion in section; and

Fig. 6 is an elevational view of the cincture as it appears after being clinched, portions thereof being broken away.

The illustrative embodiment of the invention consists of a base member 1 having in its shank or medial portion an elongated slot 2, at its forward end an upturned bifurcated hook 3, and

5 at its rear end an internally threaded lug 4. Upon the shank is removably positioned a slideable block 5 provided with a guide lug 6 that projects into the slot 2 in the shank, and a peg 7 projects from the block loosely through said slot, and is provided at its lower end with a cross-head 8 wherefore to secure to secure the block in operative position on the shank so that longitudinal movement of the block on the shank, while the lug is in the slot, is permitted.

10 A threaded operating rod 9 extends through the lug 4 and is provided at its forward end with a grooved nib 10 that projects into a cavity 11 made in the rear end of the block, and a lock-screw 12 disposed in said block extends into the groove of the nib wherefore to secure the operating rod and block together while permitting free turning movement of the rod. Upon rotation of the rod the block is adjustably moved 15 on the shank.

15 In the forward end of the block 5 is secured a jaw 13 having limited fore and aft pivotal movement relative thereto and disposed oppositely with respect to the hook 3, the jaw being arranged so as to stand erect in operative position when the instrument is applied, and drop down upon the shank out of the way to permit removal of the instrument from the situs without encroachment of the jaw upon tissues about 20 the incision. When the jaw 13 is in erect position, the forward end of the block 5 and the front of the jaw present a continuous bone-contacting face.

25 A feature of the invention is the preferred form of the hook 3 which has upward curvature and is fork-shaped. The concave faces of its tines have made therein transverse serrations 14 to enhance its gripping properties. An arcuate web 15 is disposed between the tines and 30 extends across the space therebetween to form an upwardly inclined deflector. In this manner the back of the hook is closed by the web, and the opposite face of the hook has an arcuate cavity 16 between its tines open at its upper end. 35 There are also divergent channels 17 made in the upper face of the hook at its juncture with the shank which extend from the sides thereof leading into the cavity 16.

40 For use in conjunction with the bone clamp 50 there is provided a cincture which is applied around the bone while the fragments thereof are temporarily held in place by the bone clamp and which remains in place for a protracted period following removal of the clamp. A preferred form of a suitable cincture is shown in Figs. 5 and 6.

In this instance the cincture consists of a pliant tie wire 18 one extremity of which is backturned to form a bead 19 by which to blunt the leading end of the wire, and the opposite end of the wire has connected thereon a shackle consisting of a tube 20, the wire being looped loosely through the wall of the tube adjacent one end thereof.

In operation, an incision is made through the flesh of the injured member to expose the bone at the place of fracture, the bone fragments are then reduced as in the usual practice and the instrument is inserted through the incision and the hook is moved into position back of the bone, after which, by manipulating the operating rod 9, the block with its pivoted jaw are progressed along the shank toward the hook and consequently the bone fragments become clamped by the adjacent end of the block and said jaw against the hook. While the fragments are thus firmly held in position the blunt end of the tie wire is introduced through one of the channels 17 between the jaw and the overlying bone into the cavity 16 and thrust against the arcuate web by which the wire is caused to curve upwardly during its passage and encircles the bone. The beaded end of the wire is then severed, the remaining end portion of the wire is inserted through the tube 20, and the projecting end of the wire is grasped by use of any suitable instrument (not shown) with which traction is applied to the wire while counter-traction is made against the outer end of the tube. Thus, the wire is formed into a loop 21 that encircles and is drawn tight around the bone. While the wire is thus held taut it is backturned over the outer end of the tube against the exterior wall thereof as indicated at 22 to prevent slackening of the wire loop. A suitable protective shield, such as a length of rubber tubing (not shown) is placed over the outer end of the tube and the backturned or clinched end 22 of the wire to prevent interference with gauze or other superficial dressing applied to the wound.

After fixation of the bone fragments has been established by the cincture, if desired, a cast (not shown) is applied around the injured member, leaving an open void in the cast surrounding the shank of the instrument, after which by manipulation of the operating rod the block with its pivoted jaw are moved backwardly, whereupon the jaw drops out of the way automatically onto the shank thereby permitting greater freedom of movement of the instrument as it is withdrawn from engagement with the bone, which is advantageous, as is thereby obviated interference of the pivoted jaw with the exposed flesh and obstruction by the surrounding wall of the cast.

When convalescence has progressed sufficiently to permit removal of the cincture, the bent end 22 of the wire is severed, counter-traction is applied to the tube 20 while concurrently counter pressure is made against the bone, the operation being carried out with the use of any suitable

instruments (not shown) as are appropriate for operations of that character.

To facilitate sterilization, the instrument is constructed so as to permit dismemberment and reassemblage of its parts readily. For instance: By first removing the lock-screw the operating rod is disconnected from the block upon unscrewing the rod out of the lug in which it is threaded, whereupon by raising the rear end of the block sufficiently to clear the guide lug from the slot in the shank the block is free to be turned laterally upon the axis of the peg to a position at right angles to the shank to permit withdrawal of the cross-head through the guide slot. Thus, the several parts may be subjected advantageously to sterilization separately.

Variations from the particular construction above disclosed may be resorted to by the exercise of skill in the art, without departure from the spirit or scope of the invention, and the following claims are intended to be inclusive of such variations.

What I claim is:

1. In a surgical bone clamp, a base member having at one end an upwardly curved bifurcated hook provided with an upturned arcuate cavity and at its other end a threaded lug, an arcuate web disposed between the tines of said hook providing a deflector, said hook having channels at its juncture with said member in the upper face thereof, a block longitudinally movable on said member provided with a pivoted jaw opposed to the hook and having limited pivotal movement thereon toward and from said hook the forward surfaces of said block and jaw affording a continuous bone-contacting face, and an operating threaded rod extending through said lug connected with said block for actuating the block.

2. In a surgical bone clamp, a base member having at one end a threaded lug and at its other end an upwardly curved hook provided with a deflector cavity and having in its upper face at its juncture with said member an open channel for the passage therethrough of a cincture wire into said cavity, a block longitudinally movable on said member toward and from said hook and provided with a pivoted upstanding jaw opposing said hook, the forward surfaces of said block and jaw presenting a continuous bone-contacting face and a threaded operating rod extending through said lug and engaging said block for actuating the block.

3. A surgical bone clamp consisting of a base having at one end an upturned hook and a threaded lug at its other end, a movable member on said base provided with an abrupt forward end and a pivoted upstanding jaw that affords together with the said abrupt end a continuous bone-contacting face opposed to said hook, and a threaded operating rod in said lug connected with said member for adjusting same on said base.

GEORGE S. HACKETT.
